Application March 14, 1946, Serial No. 654,430

10 Claims. (Cl. 212—108)

1

This invention relates to cabinets of the type commonly known as "built-in" cabinets such as are frequently placed in kitchens and bathrooms. These cabinets must be easily transported and installed, capable of being used as a single or multi-sectional unit, attractive in appearance, and economical.

Therefore, an object of the present invention is to provide an improved cabinet construction, employing prefabricated parts, which can be shipped "knocked-down" as an assembly kit and easily installed where desired, thus reducing shipping costs and damage in transit.

Another object of the invention is to provide a cabinet construction of the "built-in" type such that one or more walls of the cabinet are provided by the walls of the room in which the cabinet is installed.

A further object of the invention is to provide an improved cabinet construction of prefabricated parts which are susceptible of mass production and readily assembled as either a single or multi-sectional unit.

A still further object of the invention is to provide an improved cabinet construction which employs prefabricated, substantially rectangular, frame members, adapted to be attached to one or more walls of a room, to form the corners of a cabinet, the said frame members being also adapted to receive a plurality of horizontally extending members to form compartments in the cabinet.

It is also an object of the invention to provide an improved cabinet construction which employs prefabricated, substantially rectangular, frame members adapted to be attached to a wall and ceiling of a room to form the corners of a ceiling or wall cabinet.

It is also an object of the invention to provide an improved cabinet construction which employs prefabricated frame members, adapted to be attached to one or more walls of a room, to provide the corners of a wall and floor supported cabinet, said frame members having means thereon forming guideways for one or more drawers in the completed cabinet; said frame members also forming the support for a top and sides of the finished cabinet.

Other objects and advantages of the invention will become apparent from the following detailed description when taken in conjunction with the accompanying drawings, wherein:

Fig. 1 is a perspective view of a cabinet, constructed in accordance with this invention, showing two sections united together to form a single

2

unit which is mounted in the corner of a room;

Fig. 2 is an exploded view of the cabinet shown in Fig. 1 illustrating the improved frame members and their mode of assembly with panels

5 forming the top, shelves and a side;

Fig. 3 is a fragmentary top planar view of the rear corner of the cabinet top illustrated in Fig. 1, a portion of the top surface being broken away to illustrate the flange employed for mounting

10 the top on the frame members;

Fig. 4 is a perspective view of a modified cabinet having a plurality of shelves and drawers, constructed in accordance with this invention, with the shelves, top, and one side each formed

15 from single panels of wood, the drawers and doors being removed;

Fig. 5 is a sectional view taken on the section line 5—5 of Fig. 4 and illustrating the base member and its mode of connection to the front of

20 the cabinet which is partially supported thereby;

Fig. 6 is a fragmentary view of the front portion of one of the frame members illustrated in Fig. 4 showing on an enlarged scale, the details of the drawer guide attached thereto;

25 Fig. 7 is a perspective, partially exploded, view of the cabinet shown in Fig. 4 showing the drawers and doors which are to be assembled therewith to form the completed cabinet;

Fig. 8 is a perspective view of a cabinet, constructed in accordance with this invention, and attached to the ceiling and a wall of a room;

Fig. 9 is a perspective view of the frame members and shelves employed in the cabinet of Fig. 8, the parts being shown in detached relationship

35 prior to their assembly in a completed cabinet;

Fig. 10 is a perspective view illustrating the frame members and shelves of the cabinet of Fig. 8 in their assembled positions and also showing, in spaced relationship, the side panel which is

40 to be attached thereto; and,

Fig. 11 is a perspective view illustrating a single section cabinet constructed in accordance with the invention.

Before describing the detailed features of the 45 cabinets and their construction constituting this invention, it should be noted that an essential feature of the invention resides in the fact that the cabinets are of a "built-in" type so that one or more of their sides are formed by the walls 50 and/or ceiling of a room in which they are placed; the said walls and/or ceiling also serving as the main supporting means for the cabinets so that important savings in materials are effected. Also, the construction is such that the 55 elements forming each cabinet may be shipped

in "knocked-down" condition and assembled on the job to fit the requirements of each particular installation. Furthermore, the construction is such that the cabinets may be assembled as separate units or as a continuous series of units in any desired combination.

Turning now to Fig. 1 of the drawings, the cabinet illustrated therein comprises two sections, one section having three drawers arranged in vertical relationship and the other section having a drawer at the top with a plurality of shelves therebelow. These two sections are mounted in the corner of a room so that one of the walls, A, thereof forms one side for the unit and the other wall, B, forms the back of the completed cabinet, the details of the internal construction being illustrated in Fig. 2.

As shown in Fig. 2, a plurality of vertical frame members 10, 11, 12 and 13 are provided to form the corners of the cabinet assembly illustrated in Fig. 1. Each of these frame members is shown as formed from a single strip of metal, having a channel-shaped cross section, and shaped to a generally rectangular configuration with one side of the rectangle (in this case the top) being incomplete. A plurality of holes are provided at spaced points along the webs of the channel-shaped frame members for attachment to a wall of the room and for connection of the other elements of the cabinet in a manner which will be subsequently described. While I have illustrated these frame members as each formed from a single strip of channel-shaped metal, it will, of course, be obvious that a similar construction can be provided by employing materials other than metal and by forming the frame members from a plurality rather than from a single piece of material. Also, the channel-shaped cross section of the frame members is not essential but provides a relatively rigid construction when light-weight materials are employed.

The frame members 10 and 11, forming the corners for the left hand section of the cabinet shown in Fig. 1, are shown as being provided with a plurality of horizontally extending channel-shaped members 14 which may be welded or otherwise secured to the inner flanges of the frame members 10 and 11. These latter channel-shaped members 14 provide the guideways for the drawers 15 which are employed in the cabinet and to facilitate the sliding of these drawers within the guideways, the forward edge of the lower flange of members 14 is provided with a roller 16, upon which the drawer 15 rides. The means for guiding the drawers 15 in the guideways formed by the channel-shaped members 14 may be formed in a variety of ways well known in the art. For the purpose of illustration, I have shown this guide means as constituting a small roller or bearing 17 attached to the lower rear portion of the sides of the drawers 15 (see Fig. 7). The frame members 12 and 13 are similar to the frame members 10 and 11, except that each of the former has but one channel-shaped member 14 secured thereto to form a drawer guideway.

The frame members 10, 11, 12 and 13 are placed in upright position in planes extending normal to the wall of the room on which they are to be mounted and are attached to the said wall by means of screws or other fastening means passing through certain of the spaced holes 18 in the frame members and into the wall therebehind. The spacing between the frame members 10 and 11 corresponds to the width of the drawers 15 and similarly the spacing between the members

12 and 13 is substantially that of the drawer 15. The frame members 11 and 12 are placed closely adjacent each other and may be connected together by means of connecting plates 19 provided with holes through which stove bolts, self-tapping screws, or other connecting means may pass for cooperation with certain of the holes 18 in the frame members 11 and 12. These connecting plates 19 are provided to strengthen the cabinet construction and prevent the sections thereof from separating slightly. The connecting plates 19 are not, however, essential and may be omitted if desired.

In mounting the frame members 10, 11, 12 and 13 upon the wall of the room, the lower transverse portion 20 of the said members is spaced upwardly from the floor of the room. In order to close this space and provide a support for the front of the cabinets, base panel members 21 are provided which may be attached by any suitable means, such as stove bolts, to holes 18 in the forward portion of the said transverse side 20 of the frame members. These base panels 21 may be formed from sheet metal having inturned flanges 22 along their longitudinal edges in which suitable holes are provided for the aforementioned connection to the frame members 10, 11, 12 and 13. In the embodiment illustrated in Figs. 1 and 2 it will be observed that the end frame member 10 lies against the wall A of the room so that this side of the cabinet is closed by the said wall and no side panel is needed. Likewise, since the frame members 10, 11, 12 and 13 are connected to the wall B, no rear panel is needed for the cabinets. The right-hand side of the cabinet is illustrated as being closed by a panel member 22 which may be formed from sheet metal having inturned flanges provided with spaced holes therein for attachment to the frame member 13, as will be apparent from Fig. 2. The front flange of the side panel 22 may be provided with rectangular cut-out portions 23 to expose a portion of the frame member 13 at spaced points along its front side.

The top of each of the cabinets is provided with sheet metal panels 27 of identical construction. These panels have downwardly and inwardly extending flanges 28 on the front and sides thereof, as is shown in Fig. 3. The inwardly extending flanges 28 are parallel with and spaced from the top surface of the panels 27 and suitable holes 29 are provided in the said flanges for connection to the upper side of the frame members 10, 11, 12 and 13. The space within the right-hand cabinet 55 of Fig. 1, below the single drawer 15, may be divided into several compartments by means of shelves 30 (see Fig. 2), which are formed from sheet metal panels provided with flanges having holes adjacent the corners for attachment to the holes 18 in the frame members.

A door 24 is provided to close the front of the shelf portion of the right-hand section of the cabinet illustrated in Figs. 1 and 2, the door being provided with conventional hinges 25 (see Fig. 7) which are attached to the frame member 13 at the points corresponding to the cut-out portions 23 in the front flange of side panel 22. The space below the frame member 13 at the side of the cabinet may be closed by a base panel 26 similar to the previously described base panel 21.

While the construction of the cabinets illustrated in Figs. 1 and 2 has been described as formed from metal frame members and sheet metal panels, it is obvious that other materials may be employed while retaining the essential

features of this invention. For example, I have illustrated in Fig. 4 a two unit cabinet installed in the corner of a room having walls A and B in a manner similar to the cabinets illustrated in Figs. 1 and 2. However, in the construction illustrated in Fig. 4 the shelves 31 and the top 32 are each formed by a single panel of wood extending over the entire width of the two cabinets. The vertical frame members 33, 34, 35 are similar to the frame members 12 and 13 illustrated in Fig. 2, the right-hand frame member for the cabinet of Fig. 4 being obscured by the side wall 36. The top 32 and shelves 31 are attached to the frame members by screws, nails or other suitable fastening means passing through the holes in the said frame members. In the same manner, the wooden panel 36 forming the side of the cabinet, is attached to the right-hand frame member (not shown). The front of the cabinet is supported, and the space between the frame members and the floor is closed, by the base member 37, which is simply a wooden strip or timber. Likewise, the space at the side of the cabinet between the floor and the lower frame members is closed, and the cabinet supported, by the wooden base member 38. Each section of the cabinet illustrated in Fig. 4 is provided with a drawer 15 and a door 24 (see Fig. 7), the frame members for the cabinet each having a drawer guideway 14' attached thereto for receiving and guiding the drawers 15, the sliding of which is facilitated by rollers 16' attached to the guideways. The elements 14' and 16' are identical in nature and function with the guideway 14 and roller 16 previously described. These drawers and doors may, of course, be formed of either wood or metal, and the drawers are provided with the aforementioned rollers 17 for guiding the drawers within the guideways formed by the channel-shaped members 14'. Suitable handles or knobs 47 and 48 are provided on the drawers and doors, respectively, and the latter may be provided with suitable latches to retain them in a closed position.

Turning now to Fig. 8, I have illustrated a two unit cabinet constructed in accordance with this invention and installed in the upper corner formed by the walls A and B and ceiling C of a room. In a cabinet of this construction, the corners are provided by vertical frame members 40, 41, 42 and 43 respectively. These frame members have a rectangular configuration with the rear vertical side incomplete. The side frame members may be constructed from a single strip of metal having a channel-shaped cross section as shown, or may be formed from other materials and from more than one piece if desired. The web of the channel in the frame members 40 to 43 has a plurality of spaced holes 44 to provide means for attaching the said frame members to the walls and ceiling of the room and also for attaching shelves and doors thereto.

These frame members 40, 41, 42 and 43 are mounted in vertical upright positions with their planes extending normal to the walls B so that the rear vertical sides are in contact with said wall to which they are connected by fastening means passing through certain of the aforementioned holes 44. The upper sides of the said frame members are each in contact with the ceiling C and attached thereto by suitable fastening means passing through others of the said spaced holes 44. The frame member 40 is placed in contact with, or slightly spaced from, wall A so that the said wall A forms the left side for

the completed cabinet unit. A plurality of shelves 45 are provided for the cabinet by panels of sheet metal or wood similar to the panels 30 or 31 previously described. These shelves 45 are connected in horizontal, vertically spaced relationship with the frame members 40, 41, 42 and 43 by suitable fastening means passing through selected ones of the holes 44, the lower shelves 45 also serving as the bottom of the cabinet. A side 10 for the right of the cabinet is provided by a panel member 46 which is secured to the right-hand frame member 43 by suitable fastening means. A closure for the front of the cabinet is provided by a pair of doors 24, swingingly mounted upon the vertical frame members and provided with suitable knobs or handles 48.

A single unit cabinet constructed in accordance with this invention is shown in perspective view in Fig. 11. This cabinet is of the type which is supported by one wall and the floor of a room in the manner previously described for the cabinets illustrated in the Figs. 1 to 7 inclusive. As illustrated, the cabinet comprises a single drawer 15 and a plurality of shelves 49 which are supported upon frame members (not shown) similar to the frame members 12 and 13 of Fig. 2. These shelves may be either metal panels such as the shelves 30 of Fig. 2, or wooden boards such as the shelves 31 of Fig. 4. Likewise, the cabinet is provided with a top 50 which may be either wood or metal and is attached to the top of the frame members in the manner previously described. Base panel members 51 and 52 (similar to panels 21 and 26 or timbers 37 and 38) are provided to support the cabinet and close the space between the lower portion thereof and the floor. If the cabinet be installed against two walls of a room, in the manner shown in the Figs. 1 and 4, only one side panel 53 is necessary. On the other hand, if it be desired to have the cabinet mounted against only one wall, a second side panel, identical with 53, is provided for the other side of the cabinet, and a second side base member corresponding to 52, is likewise provided for the left side of the cabinet. The shelf portion of the cabinet is closed by a door 24 constructed of wood, metal or other materials hingedly mounted to one of the vertical frame members.

It will be apparent that while this cabinet has been illustrated as having one drawer and a plurality of shelves to form a plurality of compartments, a number of variations as to the divisions of the cabinet into the compartments may be made. For example, by providing sufficient horizontal guideways, the entire space of the cabinet 55 may be utilized for drawers; or the entire space may be given over to shelves. Also, if desired, certain of the shelves may be omitted if storage space of greater height is desired.

It will now be apparent that the improved construction disclosed provides means whereby cabinets of the "built-in" type may be installed as single units or multi-sectional units so that one or more sides thereof are formed by the walls and/or ceiling of a room, which walls and/or ceiling 60 may also provide a part of the support for the cabinet. The elements making up the cabinet are few in number and consist of a plurality of frame members and panels which may be prefabricated to standard sizes and shipped "knock-down" to the point where they are to be assembled and installed, thus conserving space in shipping, with resultant reduction in cost. By proper selection of the size of the panels forming the top, sides, shelves, and doors, and by se-

lection of drawers of desired widths, the same frame members may be used for assembling cabinets of different sizes so as to adapt them to the space requirements in the room where they are to be installed. Moreover, by the use of suitable frame members the interiors of the cabinets may be divided into a plurality of compartments comprising all drawers, all shelves, or any desired combinations of shelves and drawers.

For the purposes of illustration, the cabinets have been shown only as formed of one or two sections. It will be obvious, however, that additional sections of any desired number may be added so that the cabinet unit will extend along one entire wall of a room in which event no side panels are necessary. Also, as heretofore indicated, the material of construction may be wood, metal or other materials or combinations of these and that when multi-sectional units are formed with wooden shelves and top, these members may be each single boards of sufficient length to extend the entire width of the finished cabinet or may be formed of separate members, each having the width of a single section of the unit.

While I have disclosed preferred embodiments of the invention in considerable detail, I do not wish to be confined to the exact constructions illustrated but desire to cover all modifications coming within the spirit and scope of my invention as set forth in the appended claims.

Having thus described my invention, I claim:

1. A prefabricated cabinet for installation against a wall comprising, a plurality of pre-formed frame members each comprising a single elongated piece of metal bent to a substantially quadrangular configuration and having a plurality of holes therein, said frame members being disposed in spaced upright positions with their planes normal to the wall and with one vertical side of each such frame member lying against and adapted to be connected to said wall by fastening means passing through certain of said holes, said frame members constituting the corner posts of the cabinet, a plurality of horizontally extending members carried by the vertical sides of said frame members to provide a plurality of compartments in said cabinet, panel means for closing one or more sides of said cabinet, and fastening means passing through others of said holes in the frame members to secure the panel means thereto.

2. A prefabricated cabinet for installation against a wall comprising, a plurality of pre-formed frame members each comprising a single elongated piece of metal bent to a substantially rectangular configuration and adapted to be disposed in upright substantially parallel spaced relationship extending normal to the plane of said wall, the said frame members each having spaced holes in the rear vertical portion thereof for receiving fastening means adapted to secure the frame members to said wall, a plurality of vertically spaced substantially flat preformed sheet metal panels extending between said frame members and connected thereto and including panels forming the top and one or more shelves for the cabinet, a door for the front of the cabinet, means movably mounting said door on one of said frame members, and a preformed side forming sheet metal panel disposed in upright relation and connected to one of said frame members for closing the cabinet on a side thereof.

3. In a cabinet structure of the character described adapted to be installed against a wall of

a room, a plurality of spaced upright frame members each comprising a single elongated piece of metal bent to a substantially rectangular configuration and disposed so that the vertical sides of the frame members form the corner posts of the cabinet, the rear vertical portions of said frame members being provided with holes for receiving fastening means adapted to secure the said frame members to a wall of said room, other frame members extending in a direction from front to back in spaced substantially parallel relation and connected to the vertical sides of said rectangularly shaped frame members, said other frame members being of channel cross-section and forming a runway in the cabinet for a drawer or the like, and a plurality of panels connected to said rectangularly shaped frame members to form the top and at least one side for the cabinet.

4. A prefabricated cabinet for installation against a wall of a room having a floor comprising, a plurality of preformed frame members each comprising a single elongated piece of metal bent to a substantially rectangular configuration and adapted to be disposed in spaced upright relationship extending substantially normal to the plane of the wall with one of the vertical sides of each such frame member lying against and adapted to be connected to the wall and with the transverse portions of the frame members spaced from said floor, preformed shelf-forming sheet metal panels extending between said frame members at spaced elevations and connected thereto, a preformed upright side-forming sheet metal panel connected to one of said frame members for closing the cabinet on one side thereof, and a sheet metal member forming a front closure for the space between said frame members and floor and having supporting engagement with the frame members at a point spaced from said wall.

5. In a prefabricated cabinet for installation against a wall of a room having a ceiling, a plurality of preformed frame members each comprising a single elongated piece of metal bent to a substantially rectangular configuration and adapted to be disposed in spaced upright relationship extending substantially normal to the plane of said wall with one vertical side of each such frame member lying against and adapted to be connected to the wall and with the upper side of the frame members adapted to be connected to said ceiling, preformed shelf-forming sheet metal panels extending horizontally between said frame members at spaced elevations and connected thereto, and a preformed upright side-forming sheet metal panel connected to one of said frame members for closing the cabinet on a side thereof.

6. In a prefabricated cabinet for installation against a wall of a room having a ceiling, a plurality of preformed frame members each comprising a single elongated piece of metal bent to a substantially rectangular configuration and adapted to be disposed in spaced upright relationship extending substantially normal to the plane of said wall with one vertical side of each such frame member lying against and adapted to be connected to the wall and with the upper side of the frame members adapted to be connected to said ceiling, preformed shelf-forming panels extending horizontally between said frame members at spaced elevations connected thereto, and one or more doors movably connected to the front vertical sides of said frame members, and a preformed upright side-forming sheet metal panel

connected to one of said frame members for closing the cabinet on a side thereof.

7. In a prefabricated cabinet for installation against a wall of a room having a floor comprising, a plurality of preformed frame members each comprising a single elongated piece of metal bent to a substantially rectangular configuration and adapted to be disposed in upright relationship extending substantially normal to the plane of the wall with one of the vertical sides of each such frame member lying against and adapted to be connected to the wall and with the transverse portions of the frame members spaced from said floor, said frame members being alternately spaced from and closely adjacent each other, means for connecting the vertical sides of said adjacent frame members together, a panel-like members forming a front closure for the space between said frame members and floor and having supporting engagement with the frame members at a point spaced from said wall, vertically spaced horizontally extending guideways connected to the two vertical sides of each of a pair of said spaced frame members, a plurality of drawers having guiding means for cooperation with said guideways to enable said drawers to be moved into and out of the space between said pair of frame members, a plurality of shelf-forming panels extending between others of said spaced frame members at spaced elevations and connected thereto, and a door movably mounted on one of said last-mentioned frame members to form a movable closure for the shelf space provided by said shelf-forming panels.

8. In a prefabricated cabinet for installation against a wall of a room having a floor comprising, a plurality of preformed frame members each comprising a single elongated piece of metal bent to a substantially rectangular configuration and adapted to be disposed in upright relationship extending substantially normal to the plane of the wall with one of the vertical sides of each of such frame members lying against and adapted to be connected to the wall and with the transverse portions of the frame members spaced from said floor, said frame members being alternately spaced from and closely adjacent each other, means for connecting the vertical sides of said adjacent frame members together, a panel-like member forming a front closure for the space between said frame members and floor and having supporting engagement with the frame members at a point spaced from said wall, a plurality of horizontally extending members carried by the vertical sides

of said frame members to provide a plurality of compartments in said cabinet, and a plurality of panel members connected to said frame members to form a top and at least one side for said cabinet.

5 9. A prefabricated cabinet comprising, a plurality of preformed metal frame members each comprising a single elongated piece of metal bent to a substantially quadrangular configuration and having a plurality of spaced holes therein, said frame members being adapted to form the corners of a finished cabinet when attached to the wall of a building in a vertical position with the plane of each frame member normal to the plane of said wall, a plurality of sheet metal panels having marginal flanges provided with holes spaced to correspond with certain of the holes in the frame members so that said panels may be connected to the said frame members to form shelves and one or more exterior walls of the completed cabinet, and one or more doors provided with hinges adapted to be connected with the frame members to provide a movable closure for the front of the completed cabinet.

10 15 10. A prefabricated cabinet comprising, a plurality of preformed frame members each comprising a single elongated piece of metal bent to a substantially rectangular configuration and having a plurality of spaced holes therein, said frame members being adapted to form the corners of a finished cabinet when attached to the wall of a building in a vertical position with the plane of each frame member normal to the plane of said wall, drawer guideways connected to at least two of said frame members in spaced parallel relationship and extending transversely thereof, one or more drawers having guiding means for reception in said guideways of the assembled cabinet, and a plurality of panels adapted to be connected with certain of the holes in said frame members to provide a top and shelves for the completed cabinet.
